DRAFTING TAPE DISPENSER OR THE LIKE

Howard A. Powers, Medfield, Mass., assignor to W. H. Brady Company, Milwaukee, Wis., a corporation of Wisconsin

Filed Jan. 29, 1963, Ser. No. 73,367

Term of patent 14 years

(Cl. D74—1)

FIG. 1 is a front elevational view of a drafting tape dispenser or the like showing my new design;

FIG. 2 is a right side elevational view thereof;

FIG. 3 is a rear elevational view;

FIG. 4 is a top plan view of FIG. 1;

FIG. 5 is a bottom plan view thereof; and

FIG. 6 is a fragmentary elevational view of the left side bottom portion of FIG. 1.

I claim:

The ornamental design for a drafting tape dispenser or the like, substantially as shown.
